UNITED STATES PATENT OFFICE

MYRTLE E. SEYFERTH, OF MURPHYSBORO, ILLINOIS

COLLAPSIBLE BED OR CRIB

Application filed June 15, 1931. Serial No. 544,654.

The invention relates to a bed or crib construction and more especially to a collapsible or folding baby's crib.

A primary object of the invention is the provision of a structure of this character wherein the sides and ends of the bed or crib can be extended or folded and when in extended position will be held firm and rigid for occupancy for sleeping or reclining purposes and when folded permits the structure to be stored or placed within a restricted area as it occupies a minimum of space.

Another object of the invention is the provision of a structure of this character, wherein the same is novel in form so that it can be carried conveniently for transporting the same from one point to another when not occupied, as for example, when traveling by automobile or when being shipped from one point to another and is readily portable, as it is capable of being extended for use or folded when not in use.

A further object of the invention is the provision of a structure of this character, wherein the sides and ends are of novel form to permit the extending or contracting thereof and when extended the same will be braced to prevent accidental collapsing or folding.

A still further object of the invention is the provision of a structure of this character which is extremely simple in its make-up, neat and attractive in appearance, readily and easily adjusted to extend the same or fold it, thoroughly reliable and efficient in its purpose, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:—

Figure 1 is an elevation of a structure in accordance with the invention, the same being extended for use.

Figure 2 is an end elevation.

Figure 3 is a side elevation with the structure folded.

Figure 4 is an end elevation with the structure folded.

Figure 5 is a top plan view of the structure extended, the same being partly broken away to illustrate details.

Figure 6 is a sectional view on the line 6—6 of Figure 1 looking in the direction of the arrows.

Figure 7 is a sectional view on the line 7—7 of Figure 2 looking in the direction of the arrows.

Figure 8 is an enlarged fragmentary vertical sectional view through one of the end posts and adjacent parts showing in detail the manner of fastening the top side rail to the end posts.

Similar reference characters indicate corresponding parts throughout the several views in the drawings.

Referring to the drawings in detail, the bed or crib structure comprises vertical corner posts A, each being preferably of square formation in cross section yet they may be otherwise shaped and made from any suitable material. The posts A carry suitable casters B journaled in their lower ends so that the structure can be moved conveniently upon a foundation, floor or other support.

Arranged between the posts A both at the top and bottom ends and also at the sides of the bed or crib structure are vertical slats or guard bars 10, these at opposite ends being fitted with coupling plates 11, while between the said slats or bars 10 are upper and lower series of outwardly breaking hinges 12, the outermost ones of each series being provided with an attaching plate 13 which is made secure or fast to the corner posts A adjacent thereto by fasteners 14.

so that in this manner the posts A are connected with the slats or bars 10 whereby the framing constituted thereby can be extended or folded as should be apparent. The hinges 12 are swingingly connected to the plates 11 as at 14' in hinge fashion and in this manner the bed or crib framing structure is unitary but susceptible of extension and contraction.

Adapted to be superimposed upon the top series of connected plates 11 and hinges 12 when the bed or crib frame is extended are top rails 15, each having in each end thereof a nut 16 countersunk therein and retained by a plate 17 made fast thereto, the plate 17 being also countersunk while removably fitted in a bore 18 formed transversely in each post A is a securing bolt 19 having a winged head 20, this plate being threaded into the nut 16 when removably inserted in the bore 18 in the posts A so as to detachably join the rail 15 and said posts as is clearly shown in Figure 8 of the drawings. The rail 15 is formed with a longitudinal channel 21 which accommodates the plates 11 and hinges 12 when the same are in the same plane with each other on the extending of the bed or crib structure and such plates 11 and hinges 12 will be concealed within the top rail 15 as will be apparent. In this manner the bed or crib frame will be rigidly maintained extended for the occupancy of the bed or crib.

Adapted to be arranged between the posts A immediately beneath the lower series of plates 11 and hinges 12 are side and end bottom rails 22 and 22' respectively and these at their ends are fastened as at 23 identical with the rails 15. Each end rail 22' is substantially of angle formation in cross section and also accommodates the plates 11 and hinges 12 to conceal the same as shown in Figure 7 of the drawings. The rails 22' at opposite ends of the bed or crib carry fasteners 24 for the detachable mounting thereof of a bed or crib spring (not shown).

It will be observed that when the top rail 15 and bottom rails 22 and 22', the said rail 22 being similar to the rail 15—are detached from the post A by releasing the fasteners or bolts 19 and 23 the folding or collapsing of the bed or crib structure may be effected. When the bed or crib is extended it is for occupancy, and on contracting or collapsing thereof the same may be conveniently transported and located in a restricted area as it will occupy minimum space.

What is claimed is:—

In a structure of the kind described, corner posts, vertical guard bars arranged between the posts, coupling plates secured to opposite ends of the bars, upper and lower series of outwardly breaking hinges pivotally fitted with the coupling plates, means connecting the upper and lower series of

hinges with the posts, channeled top and bottom rails respectively receiving in their channels the upper and lower series of hinges and coupling plates when extended to lie in the same plane with each other, and means detachably connecting the top and bottom rails with the posts.

In testimony whereof I affix my signature.
